CLIFFORD B. ARNOLD AND ALBERT K. PRATT, OF WHITINSVILLE, MASSACHUSETTS, ASSIGNORS TO THE WHITIN MACHINE WORKS, INCORPORATED, OF WHITINSVILLE, MASSACHUSETTS.

LENO-MOTION FOR LOOM-DOBBIES.

SPECIFICATION forming part of Letters Patent No. 764,223, dated July 5, 1904.

Application filed January 7, 1903. Serial No. 138,098. (No model.)

To all whom it may concern:

Be it known that we, CLIFFORD B. ARNOLD and ALBERT K. PRATT, citizens of the United States, residing at Whitinsville, in the county of Worcester and State of Massachusetts, have invented new and useful Improvements in Leno-Motions for Loom-Dobbies, of which the following is a specification.

This invention has reference to looms, and more particularly to looms for leno-weaving where mechanism in operative connection with the loom-dobby and certain predetermined harnesses operates to give a half and return motion to the harnesses.

In weaving leno it is necessary to cross certain warp-threads and to give to certain predetermined harnesses a half and return movement during the cross-weaving or a movement that will carry such warp-threads from the plane of the open shed to an intermediate point and back to the original plane. This is done by mechanism connecting the dobby with the harnesses controlling the warp-threads used in cross-weaving, operated independent of the harness-levers, but controlled by the harness-levers when not in use for cross-weaving to give a full movement to the harnesses.

The object of our invention is to simplify the mechanism used in leno-weaving and to operate the mechanism or leno-motion by an adjustable cam adjustably secured to the actuating-rocker of the dobby; and our invention consists in the peculiar and novel construction of the adjustable cam on the actuating-rocker and its connection with the leno-motion, as will be more fully described hereinafter and pointed out in the claims.

Figure 1 is a side view of a loom-dobby, showing our improved adjustable cam leno-motion. Fig. 2 is an edge view of Fig. 1, showing the spring for keeping the roll on the cam-arm in contact with the adjustable cam. Fig. 3 is a view of the adjustable cam looking from the back, and Fig. 4 is a sectional view taken through the pivot and clamping-bolt of the adjustable cam and its support.

In the drawings, *a* is the frame of the dobby;

b, the actuating-rocker; *c*, the harness-levers, and *d* the harnesses. The actuating-rocker *b* has the pivot *b'* on the dobby-frame and receives a reciprocating motion from the loom mechanism.

On the upper end *b''* of the actuating-rocker *b* we adjustably secure the cam-support *e* by the bolt *e'*, extending through the cam-support and the slot *b''* in the end *b''* of the actuating-rocker. Secured in the upper end of the cam-support is the pin *e''*, forming a pivot for the adjustable cam *E*, constructed in two parts, with the cam-faces *e''* *e''*, the overlapping wings *e''* *e''*, having the holes *e''* *e''* for the pivot-pin, and the slots *e''* *e''* for the clamping-bolt *e'*, extending through the slots and frame *a* for clamping or locking the two parts of the adjustable cam in the adjusted position.

Secured to the upper part of the dobby-frame *a* is the yoke-frame *f*, supporting the rock-shaft *f'* in the bearing *f''*, and fastened to the outer end of the rock-shaft is the cam-arm *f''*, with the roll *f''* in contact with the adjustable cam *E*. The segmental arm *g* with the curved rim *g'* is fastened to the rock-shaft on the inner side of the yoke-frame *f*, and the strap *g''* is secured at its outer end to the curved rim *g'* by the screw *g''* and at its inner end by the wire *g''* to the link *g''*, connecting by the cordings *g''* to the harnesses *d*. The harness-levers *c* extend through the links *g''* and operate on the links to give a full movement to the warp-threads when required in the regular weaving. Surrounding the rock-shaft intermediate the yoke-frame *f* and the segmental arm *g* is the coiled spring *f''* in spring tension with the cam-arm *f''* to hold the roll *f''* firmly in contact with the adjustable cam *E*.

In the operation of our improved leno-motion the cam *E*, deriving its reciprocating motion from the actuating-rocker *b*, raises and lowers the cam-arm *f''*, fastened to the rock-shaft *f'*. This in turn reciprocates the segmental arm *g* and through the strap *g''*, the link *g''*, and the cordings *g''* gives a half and return motion to the harnesses, and this motion is adjustable by raising or lowering the

two halves of the adjustable cam E and by adjusting the cam-support e on the actuating-rocker b. The operation of the leno-motion through the cam E is continuous, but acts 5 only on the harness not raised by a harness-lever in the regular weaving.

Having thus described our invention, we claim as new and desire to secure by Letters Patent—

- 10 1. In a leno-motion for looms, a plurality of harnesses, an adjustable cam receiving motion from the loom mechanism, means for giving the harnesses a full movement, and means in operative connection with the harnesses 15 and the adjustable cam to give an independent half and return movement to the harnesses by the adjustable cam, as described.
2. In a leno-motion for looms connecting with harnesses and having a rock-shaft, an 20 adjustable cam receiving motion from the loom mechanism, and means in operative connection with the rock-shaft and the adjustable cam to give a half and return movement to the harnesses by the operation of the adjustable cam, as described.
- 25 3. In a leno-motion for looms, having a rock-shaft, an actuating-rocker deriving motion from the loom mechanism, an adjustable cam secured to the actuating-rocker, and 30 means comprising a cam-arm secured to the

rock-shaft in operative connection with the adjustable cam to give a half and return movement to the harnesses through the leno-motion, as described.

4. In combination with a leno-motion for 35 looms having a rock-shaft f', an actuating-rocker b pivotally secured to the loom-dobby and deriving a reciprocating motion from the loom mechanism, the cam-support e adjustably secured to the actuating-rocker by the 40 bolt e' through the slot b³, the two-part adjustable cam E pivoted on the pin e² secured in the cam-support and having the cam-faces e³ e⁴, the overlapping wings e⁴ e⁴ with the slots e⁵ e⁶ for the fastening-bolt e', and the cam-arm 45 f³ secured to the rock-shaft f' with the roll f⁴ held firmly in contact with the adjustable cam E by the coiled spring f⁵ on the rock-shaft to give a half and return movement to the 50 predetermined number of harnesses by the reciprocating motion of the adjustable cam E, as described.

In testimony whereof we have signed our names to this specification in the presence of two subscribing witnesses.

CLIFFORD B. ARNOLD.
ALBERT K. PRATT.
